MOUNTING BRACKET FOR RAILING POSTS

Louis Blum, Pittsburgh, Pa., assignor to Blumcraft of Pittsburgh, Pittsburgh, Pa., a firm

Filed Feb. 8, 1960, Ser. No. 59,308

Term of patent 14 years

(Cl. D13—7)

Fig. 1 is a perspective view of a mounting bracket embodying my new design;

Fig. 2 is a side elevational view of the mounting bracket shown in Fig. 1;

Fig. 3 is a rear elevational view of the mounting bracket shown in Fig. 1; and

Fig. 4 is an end view of the mounting bracket shown in Fig. 1.

I claim:

The ornamental design for a mounting bracket for railing posts, as shown.
